CLAIM

I claim the ornamental design for a battery pack, as shown and described.

DESCRIPTION

FIG. 1 is a right rear top perspective view of a battery pack. FIG. 2 is a left front top perspective view of the battery pack shown in FIG. 1.

FIG. 3 is a right front top perspective view of the battery pack shown in FIG. 1.

FIG. 4 is a left side view of the battery pack shown in FIG. 1.

FIG. 5 is a right side view of the battery pack shown in FIG. 1.

FIG. 6 is a rear view of the battery pack shown in FIG. 1. FIG. 7 is a front view of the battery pack shown in FIG. 1. FIG. 8 is a top view of the battery pack shown in FIG. 1; and, FIG. 9 is a bottom view of the battery pack shown in FIG. 1.
